UNITED STATES PATENT OFFICE

JOSEPH WEISS, OF CHICAGO, ILLINOIS

DOORCHECK

Application filed October 18, 1928. Serial No. 313,199.

This invention relates to door checks, having for its object the provision of an improved device of the kind described embodying certain added convenience in operation.

Another object is to provide a door check which may be operatively applied without first returning the door to closed position, or the manipulation of latches.

Other objects and advantages of the construction employed will appear more fully in the hereinafter details when taken in connection with the accompanying drawing in which:

Figure 1 is a front elevation of a door and casing, showing my invention attached thereto.

Fig. 2 is an elevational view of the device as applied to a door in closed position.

Fig. 3 is a top view of the device operatively attached to a door frame in closed position, the door and frame being shown in section.

Fig. 4 is a transverse section taken on line 4-4 of Fig. 6, the latch member being shown in the position it occupies as the wings of the keeper are being pressed apart to admit the latch.

Fig. 5 is a transverse section taken on line 5-5 of Fig. 6, and

Fig. 6 is an enlarged perspective of my invention as applied to a door and frame, the door being shown ajar.

In the drawings, 10 designates a door hingedly secured to a frame 11. The device embodying my invention comprises a plate 12 secured by screws 13 to the door 10, the plate being formed with an integral latch 14 having a substantially arrow shaped head 15, the projecting shoulders 16 of which serve as means to lock the latch in secure position in the channel 17, formed between a pair of wings 18 and 19, having marginal rolled beadings 20 in which are secured strips 21 formed on the edge of the oblong body plate 22. The wings 18 and 19 which are thus hinged to the plate 22 by the coacting rolled beadings and strips, are resiliently pressed against the face of the plate 22, as best shown in Fig. 6, by the springs 23, the latter having coiled portions 24 wound about pins 25 also

formed integral with the marginal edges of the plate 22. The springs 23 have U-shaped yoke portions 26 which serve to press the wings 18 and 19 yieldingly against the face of plate 22, the large central slot 27 of which is overlapped thereby. The plate 22 at one end is provided with a pair of perforated lugs 28, 29 which register with a pair of corresponding lugs 30, 31 formed on a bracket 32 held to the door frame by screws 33. Pivot pins 34, 35 passed through the lugs 28, 29, 30, and 31 serve as hinges on which the keeper assembly swings.

It will be observed that the device as illustrated in Figs. 1, 2 and 3 is also provided with a hinged locking button 36 which serves, when desired, as an auxiliary locking means to be passed through the channel 17 and then turned at right angles to the keeper wings 18, 19 which can now be released only when the elongated head of the button is turned into a position parallel with the walls of the channel 17.

The operation of the device described and illustrated is as follows: Assuming the door to be ajar, the keeper member may be swung to engage the wings 18 and 19 with the head 15 of the latch. The wings, as shown in Fig. 4, will yield and permit the entrance of the latch to the position shown in Figs. 5 and 6 wherein the projecting shoulders are locked against withdrawal from the channel 17 while permitting however longitudinal movement therein. One of the chief advantages of the present construction resides in the fact that if an unauthorized person should endeavor to force his way into a house, assuming the door to be slightly ajar, the householder may snap the keeper member over the locking latch head 15 even while the door is ajar. Heretofore in actual practice it has either been necessary to return the door to closed position before the latch could be engaged with the keeper or to insert a locking button in one position into a registering slot; a method impractical under conditions described above.

Certain other fasteners have been proposed in which a locking button having an elongated head might be thrust into a slot

and then turned to check a door in the degree of movement to which it is swung upon but so far as I am aware, no means have been provided which will permit a positive instantaneous securing of a door in the manner shown and without the manipulation of additional parts. It is apparent that if a door is slightly ajar, it will be difficult to repel an unauthorized person in cases where it would be required to first close the door against the aggressions of a desperate character without the provision of means of the type now disclosed.

It is to be understood that variations and modifications may be made in form, proportion, and arrangement of the parts as shown and described; hence, I do not confine myself to the precise details save to the extent these are circumscribed within the scope of the appended claims.

What I claim as new and desire to secure by Letters Patent is:

1. In a device of the kind described, comprising in combination, a keeper and a latch, said keeper having a longitudinal slot and means to lock said latch in said slot by means of a plurality of resilient members hingedly attached to said keeper, said means including an element secured to said latch and slidably confined between said resilient members when in operative position.

2. A door check comprising in combination, a keeper hingedly secured to a door frame, a latch member secured to a door in said frame, a pair of wing members hinged to said keeper, said wing members yieldingly receiving said latch, said latch being locked within said keeper after the wing members have yielded to a predetermined extent to admit a head element secured to said latch.

3. In a device of the kind described, in combination, a keeper hingedly secured to a door frame, said keeper having a slot partially closed by a pair of wing members, a latch secured to a door in said frame, said latch having a shoulder head received in the slot, said wing members yieldingly receiving and locking said shouldered head, while permitting the entrance of said shouldered head into the slot at any point within the limits defined by said wing members, without the return of the door to closed position.

4. In a device of the kind described, in combination, a plate hingedly secured to a bracket on a door frame, said plate having a longitudinal slot, a pair of strips hingedly secured to said plate and overlapping said slot in a manner to define a comparatively narrow channel, a keeper secured to a door within said frame, said keeper having a shouldered head adapted to pass through said channel while pressing back said strips against the action of springs normally impelling said strips against the face of said

plate but diverging therefrom as said keeper member is pressed thereagainst.

5. In a device of the kind described, in combination, a plate hingedly secured to a bracket fastened to a door frame, said plate having a longitudinal slot, said slot being overlapped by a pair of strips swingingly attached to said plate and resiliently pressed against the face of the plate by a pair of springs secured on the margin of the plate, said strips defining a comparatively narrow channel therebetween registering with the said slot, a keeper member integrally formed with a plate secured to a door, said keeper member having a shouldered head adapted to enter the channel between the strips while pressing back said strips to a point where the shouldered head of the keeper passes out of contact with the strips, said strips then returning to normal position against the face of said plate and thereby slidably locking the keeper within the plate.

6. In a device of the character described, cooperating latch and keeper elements having provision for relative longitudinally slidable interlocking engagement, said elements being relatively provided with yieldable means whereby one member may be snapped laterally into engaging relation to the other member at any point within the range of the permitted relative longitudinal movement.

7. In a device of the character described, a latch element and a cooperating longitudinally slotted keeper element, one of said elements having yieldable means whereby said latch element may be pressed into engagement with the slotted portion of said keeper element transversely thereof at different points throughout the length of the slot in slidable interlocking working relation thereto.

8. In a device of the character described, a latch element including a headed stud, and a keeper element comprising a hinged hasp-like member having a longitudinal slot, said latch element and said keeper element being relatively provided with yieldable means whereby said headed stud may be snapped into slidable interlocked working engagement at any point within the length of the slotted portion of said keeper element.

9. In a device of the character described, a hinged longitudinally slotted keeper element, said keeper element having a yieldable supporting member coincident with the longitudinal wall of its slotted portion, and a latch element having a shouldered extension adapted to be pressed transversely through the slotted portion of said keeper element whereby to be retained in slidable interlocked relation to said yieldable member at any point within the length of the latter.

10. In a device of the character described, a keeper to be hingedly secured to a door

frame, said keeper having a longitudinal slot, a latch element to be secured to a door in said frame, said latch having a shouldered head, and yieldable means constituting a longitudinal wall of the slotted portion of the keeper permitting the entrance of said shouldered head of said latch element into the slot of said keeper element at any point within the length of the slot.

11. In a device of the character described, in combination with a door frame and a door hingedly mounted in said frame, a latch element mounted on the door at the swing side thereof, said latch element having a shouldered projection extending beyond the edge of the door, a keeper hingedly secured to the door frame adjacent to said latch element, said keeper having a longitudinal slot open at its end adjacent to the hinged end portion of the keeper, said shouldered projection of the latch element being engageable with the slotted portion of said keeper element when said element is in a position substantially perpendicular to the door frame and the door is closed, and yieldable means whereby said shouldered projection is permitted to enter said slot in the keeper element at any point within the limits defined by the length of said slot when the door is open.

30 In testimony whereof I have signed my name to this specification.

JOSEPH WEISS.
